SINE PLATE ANGLE WHEEL DRESSER

Anthony E. Wisne, Detroit, Mich.

Application August 9, 1943, Serial No. 498,013

5 Claims. (Cl. 125—11)

My invention pertains to improved angle determining devices for dressing wheels and for any or all other machine work.

It is an object of my invention to provide an improved angle measuring or determining device which may be quickly and conveniently set to various angles, with improved accuracy, and which is of a simple rugged construction.

It is a further object of my invention to provide an improved wheel dresser for dressing the cutting surfaces of abrasive wheels to various angles, which can be determined quickly and conveniently with great accuracy, which will embody a rugged and simple structure, and which will maintain its accurately determined angle in use and operation.

Further objects and advantages are within the scope of the invention, such as relate to the arrangement, operation and function of the related elements of the structure, to various details of construction and to combinations of parts, elements per se, and to economies of manufacture and numerous other features as will be apparent from a consideration of the specification in conjunction with the drawings disclosing specific embodiments of the invention, in which:

Fig. 1 is a side elevational view showing an angle determining and wheel dressing device in accordance with my invention;

Fig. 2 is a fragmentary sectional view taken on line 2—2 of Fig. 1 for showing the adjustable mounting of the wheel dresser bracket;

Fig. 3 is a plan view showing my improved angle determining and wheel dressing device one edge of the sine plate being partially broken away; and

Fig. 4 is a diagrammatic view showing how the device is quickly set to accurately determine a desired angle by the insertion of a known gauging member and how it is utilized to dress the cutting surfaces of an abrasive wheel to the desired angles.

Referring more particularly to Figs. 1 and 3 of the drawings, I have illustratively disclosed an embodiment of my improved wheel dresser and multi-purpose sine plate device comprising a base 11 whereupon a sine plate 13 is mounted by means of a pair of rolls 15 and 17 secured under the sine plate in a spaced apart parallel relation, as by cap screws 19 passing up through the rolls into the sine plate, as shown. The base and the sine plate are heavy members of substantial thickness, preferably cast of any suitable metal, to provide substantial strength and rigidity for accuracy. The upper and lower surfaces of the base and sine plate are plane surfaces, formed true in accordance with conventional practice, to provide the degree of accuracy desired. The rolls are of cylindrical conformations formed in accordance with usual practice to provide the de-

gree of accuracy required for the particular device and its uses.

To facilitate computation of the angles from the sines thereof, the distance between the centers of the spaced parallel rolls 15 and 17 is preferably selected to be an exact number of units of linear measurement, as five or ten inches for example, although it might be made up in the metric system or other units, if desired. To center the rolls accurately when these are clamped up to the under side of the sine plate 13, the latter is provided with accurate centering grooves 21 and 23 extending transversely in the under surface and these are so formed as to receive suitable portions of the two rolls so that a line through the centers of the rolls will be parallel to the upper surface of the sine plate so that work pieces or tools may be accurately supported thereon, as by clamping screws (not shown) passing into threaded holes 25 in the sine plate. As shown Fig. 1, the centering groove 21 on the left hand side of the sine plate, is a cut out corner, while the other is a groove 23 cut in the bottom surface a distance from the end of the plate.

As may be seen in Fig. 3, the sine plate 13 is preferably substantially narrower than the base 11. The sine roll 15 under the left-hand end of the sine plate 13 may be of a length equal to the width of the sine plate, but the base roll 17 under the right-hand end of the sine plate is elongated to a length substantially equal to the width of the base plate 11. The extended ends of the elongated roll are journaled snugly in bearing or swivel blocks 27 which, as shown in Fig. 1, are set into sockets 29 in the base and are secured therein, as by screws 31 passing up through the bottom of the base. The swivel blocks 27 are provided with a tension slot 33 opening from the bearing aperture and providing sufficient resiliency so that by passing a clamping screw 35 through between the opposite sides of the slot the journaled ends of the roll may be clamped to eliminate slack motion and provide greater accuracy. The extreme lower right-hand edge of the sine plate 13 is provided with a bevelled surface 37 to enable the sine plate to be tilted up to a greater angle than would be possible if it were a square corner.

As may be seen in Fig. 1, a right angle sine plate or wheel dresser support 39 of substantial strength and rigidity is provided as an integral part of the same casting rising at right angles to the main sine plate 13 directly above the center of the elongated base roll 17 journaled on the base. Rising from the upper edge of the right angle sine plate 39 is a bracket 41, which is square or some other noncircular cross-section, so that it is held from rotative movement as it is slidably moved up or down in a similarly shaped aperture 43 in the support. Passing transversely

through the upper end portion of the vertically adjustable bracket 41 is a wheel dresser element 45 secured therein, as by a screw 47, and carrying a diamond or suitable point 49 for dressing a wheel. Also a horizontally disposed bracket 51, of a square or other noncircular cross-section, is slidably mounted in a suitable similarly shaped guide groove 53 cut into the other side edge of the right angle sine plate 39 and secured therein as by a guide plate 55 secured by screws 57, as shown more clearly in Figs. 1 and 2. Passing transversely through the projecting end of the horizontal sliding bracket is a wheel dresser element 59 carrying a wheel dressing point 61 and secured in the bracket, as by a screw 63, for dressing the surface of an abrasive wheel 65, represented by dotted lines. Handles 66 adjust the wheel dressers.

In operation, as represented diagrammatically in Fig. 4, the lower sine plate 13 and its right angle sine plate 39 are quickly, conveniently and accurately tilted to any desired angles merely by inserting a suitable gauging member 67, or thickness gauge, on the upper surface of the base plate 11 and under the left-hand or sine roll 15. The lower sine plate 13 is tilted sufficiently to insert the gauge member 67, and the roll 15 is then lowered onto the gauge member. The dimension of the gauge member 67 required to be selected for this purpose is conveniently determinable from the sine, or other function, of the desired angle or of complementary angles, the distance between the centers of the rolls 15 and 17 being a known distance and exactly an even number of units of linear measurement. The routine is to look up the sine of the desired angle on the sine table, or other functions of the desired or complementary angles from the sine, cosine or other mathematical tables. The known distance between the roll centers being L, and the thickness of the gauge being G, sine of angle W is G/L . Or solving for G equals $L \times \sin W$. Having set the lower sine plate accurately to a desired angle, the wheel dresser elements may then be moved along lines bearing a definite relation thereto, for accurately dressing the faces of an abrasive wheel 65, as shown in Fig. 4. The wheel dressers may be moved along manually, in the slidable supports, or may be moved along by screws or other uniform driving means, as will be readily understood. Also the sine plate may be tilted to measure the angularity of a part or surface, and then the distance between the sine roll and the base plate may be measured by any suitable gauge, and the angle may be computed. A wide variety of uses for my improved sine plate, wheel dresser device, will be apparent for machine shops and similar work.

Another feature of my improved angle determining instrument is an off-set or down-set surface, represented by the dotted line 69 in Fig. 1. This groove or recess 69 has a bottom surface downset a known amount below the upper surface of the base plate for the reception of a gauge member. The amount of downset is some odd measurement which is to be used frequently for some particular operation and which is not conveniently available in gauge members, so that by selecting a commonly available gauge member and setting it down into the groove on the downset surface, the necessary odd dimension is provided

conveniently without the necessity of seeking, or making, an odd gauge member. Also I may provide a series of such down-set grooves 69' of various different graduated depths.

It is apparent that within the scope of my invention modifications and different arrangements may be made other than herein disclosed, and the present disclosure is illustrative merely, the invention comprehending variations thereof.

I claim:

1. A sine plate angle dresser comprising, a base, a sine plate, a pair of parallel rolls of the same diameters and spaced apart a known distance for supporting said sine plate upon said base for tilting to any desired angle by inserting gauge means of known thickness between one of the rolls and said base, a right angle sine plate supported on said sine plate and extending at right angles thereto, wheel dresser means, and slidable support means carried on said sine plate for supporting said wheel dresser means extendably for dressing an abrasive wheel to form surfaces at accurately determinable angles.

2. A sine plate wheel dresser in accordance with claim 1, and further characterized by said base having a downset surface offset a known odd distance from the main surface of the base for receiving gauging means for tilting the sine plate.

3. A sine plate angle wheel dresser having in combination, a base plate, a sine plate, a pair of rolls of the same diameters, said rolls being secured to the underside in a parallel relation spaced apart a known distance for tiltably supporting the sine plate upon the base plate, a right angle sine plate supported from said sine plate, wheel dresser means, and slidable support means extendably supporting the wheel dresser means from the right angle sine plate so that wheels may be dressed at angles determined by inserting gauge members of known thickness between one of said rolls and said base plate.

4. In a plane plate angle wheel dresser, a base plate, a sine plate, a pair of rolls disposed between the base plate and the sine plate, securing means for securing said rolls to the underside of said sine plate in a parallel relation and spaced apart a known distance, a pair of parallel centering grooves in the underside of said sine plate for receiving and holding said rolls parallel at said known distance center-to-center as the rolls are secured to the sine plate so that the insertion of a selected gauge of known thickness tilts the sine plate a known angle, which is readily ascertainable, the ends of one of said rolls being extended beyond the marginal limits of the sine plate, and said base plate having means for receiving and snugly journalling the extended ends of said one roll, a right angle sine plate extending from the first mentioned sine plate, wheel dresser means, support means on said right angle sine plate for slidably supporting said wheel dresser means projecting extendably therefrom for dressing an abrasive wheel to form surfaces at accurately determinable angles.

5. A sine plate angle wheel dresser in accordance with claim 4 and further characterized by said support means rising from said sine plate at right angles above the roll which is journalled to the base.

ANTHONY E. WISNE.
